Primary Examiner — Karen S Acker*Assistant Examiner* — Clare Ann Gannon(74) *Attorney, Agent, or Firm* — Larry L. Huston; Steven W. Miller(57) **CLAIM**

The ornamental design for a sheet having a pattern, as shown and described.

DESCRIPTION

FIG. 1 is a front view of a first embodiment of a sheet having a pattern;

FIG. 2 is a front view of a second embodiment of a sheet having a pattern;

FIG. 3 is a front view of a third embodiment of a sheet having a pattern;

FIG. 4 is a front view of a fourth embodiment of a sheet having a pattern;

FIG. 5 is a front view of a fifth embodiment of a sheet having a pattern; and,

FIG. 6 is a front view of a sixth embodiment of a sheet having a pattern.

The broken lines depict the boundaries of the claim and form no part thereof.
